LIGHTING FIXTURE OR THE LIKE

Joseph Donald Willis, Phoenix, Ariz.

Application September 23, 1955, Serial No. 38,079

Term of patent 14 years

(Cl. D48—20)

FIG. 1.

FIG. 2.

The dominant features of my new design are shown in solid lines.

I claim:

The ornamental design for a lighting fixture or the like, as shown and described.
